(57) **CLAIM**

(**) Term: **14 Years**

The ornamental design for a wall clock mount, as shown and described.

(21) Appl. No.: **29/308,608**

DESCRIPTION

(22) Filed: **Jun. 25, 2008**

FIG. 1 is a top, rear left perspective exploded view of a wall clock mount according to the invention;

(51) LOC (9) Cl. **08-05**

FIG. 2 is a top, rear left perspective assembled view thereof;

(52) U.S. Cl. **D8/373**

FIG. 3 is a rear elevational exploded view thereof;

(58) **Field of Classification Search** D8/349,

D8/354, 363, 373; D10/2, 21, 22; D14/251–253;

248/220.21, 220.22, 222.51, 222.52, 224.7,

248/229.1, 488, 489, 496; 211/87.01, 544

FIG. 4 is a rear elevational assembled view thereof;

See application file for complete search history.

FIG. 5 is a front elevational view thereof;

(56) **References Cited**

FIG. 6 is a front elevational exploded view thereof;

U.S. PATENT DOCUMENTS

FIG. 7 is a left elevational exploded view thereof, the right elevational exploded view being a mirror image;
